CLAIM

The ornamental design for a suspended watch holder display container, as shown and described.

DESCRIPTION

FIG. 1 is a top, front, right perspective view of a suspended watch holder display container showing our new design holding an unclaimed wristwatch;

FIG. 2 is a top, front, right perspective view thereof without the unclaimed wristwatch;

FIG. 3 is a bottom, front, left perspective view thereof;

FIG. 4 is a front elevational view thereof;

FIG. 5 is right side elevational view thereof;

FIG. 6 is a back side elevational view thereof;

FIG. 7 is a left side elevational view thereof;

FIG. 8 is a top plan view thereof; and,

FIG. 9 is a bottom plan view thereof.

The broken lines showing in FIG. 1 are for the purpose of illustrating how the claimed suspended watch holder display container holds a wristwatch and form no part of the claimed design.
